SPRING BAND

Allen Benjamin, Chicago, Ill.

Application January 5, 1946, Serial No. 639,194

2 Claims. (Cl. 63—5)

1

The present invention relates to improvements in expansible bands and particularly to a coiled spring ribbon adapted for use as a wrist band or bracelet.

The wrist band or bracelet of the present invention is fashioned from an expansible ribbon which consists of a strand of shape retaining material, such as steel wire, coiled into a continuous succession of closely related elongated loops. In the manufacture of wrist bands or bracelets the expansible ribbon is cut to desired lengths and the ends of such cut portions are joined together integrally or by means of a name plate, watch casing or other ornamental device. When the expansible ribbon is fashioned into a wrist band or bracelet, the ribbon is disposed in such manner that one of its substantially flat faces lies against the wrist of the wearer and, to avoid undue friction and possible discomfort to the wearer, said face is shaped so that the major portion of such face is maintained out of intimate contact with the wrist. The outwardly disposed face of the bracelet has the same surface configuration as the inwardly disposed face primarily to accentuate the pleasing appearance of the finished article and also to facilitate the fashioning of the wrist bands or bracelets by avoiding the need for determining the inside or outside faces thereof.

It is, therefore, an object of the present invention to provide a wrist band or bracelet of a novel construction so as to permit the bracelet to expand or contract readily without pinching the wearer or otherwise causing discomfort.

Another object of the invention is to provide a coiled expansible ribbon-like wrist band which has its opposite faces concaved circumferentially.

Another object is to provide a wrist band or the like which is not expensive to manufacture and which may be readily shaped and is highly efficient in use.

Other and further objects of the present invention will be apparent from the following description and claims and are illustrated in the accompanying drawing which illustrates a preferred embodiment and the principle thereof and which is considered to be the best mode contemplated for applying that principle. Other embodiments of the invention embodying the same or equivalent principle may be used and structural changes may be made as desired by those skilled in the art without departing from the spirit of the present invention and the purview of the appended claims.

In the drawing:

Fig. 1 is a perspective view of the improved

2

wrist band or bracelet, showing portions thereof in broken lines.

Fig. 2 is a side elevational view of a fragment of the wrist band or bracelet.

Fig. 3 is an end elevational view of the wrist band portion shown in Fig. 2.

Fig. 4 is a sectional detail view taken substantially on line 4—4 of Fig. 3.

The wrist band shown in the accompanying drawing is fashioned from an expansible spring-like ribbon consisting of a succession of elongated loops, preferably formed by the method and apparatus taught in applicant's co-pending application Serial No. 639,195, filed January 5, 1946. The spring-like expansible ribbon is cut to a desired length and the end portions thereof are brought together and joined integrally or as by means of an identification tag or the like, indicated generally at 11 in Fig. 1, so as to form an unbroken band of such size as to snugly embrace the wrist of the wearer. Such band may be easily and quickly slipped over the hand of the wearer due to the resiliency inherent in its construction and it readily adapts itself snugly to wrists of various sizes.

As best shown in Figs. 2 and 3, the expansible ribbon consists of a plurality of loops 12, each of which is elongated and which lie in a common plane so as to present substantially flat opposed faces and gracefully rounded edges. Each of the loops, which are formed by continuously winding a strand of shape-retaining material, such as for example, steel wire, about a rotating arbor, includes reaches 13 constituting the elongated opposite sides thereof. The reaches are bowed inwardly from their juncture with the semi-circular end portions 14 of the loop. This inward bowing of the reaches 13 provides, in the finished wrist band, opposed concave faces, which faces not only materially add to the general appearance of the wrist band as a whole but serve a definite purpose in that the face of the wrist band lying against the wrist of the wearer has but a minimum amount of surface contact therewith. It should be obvious that when a wrist band is in place on a wrist only the extreme end portions of the reaches 13 are in direct contact with the wrist while the intermediate bowed portions thereof are held spaced therefrom. This minimum surface contact not only minimizes the probability of any discomfort while wearing of the bracelet because of excessive rubbing friction, but further tends to maintain the closely spaced reaches 13 a sufficient distance from the surface of the wearer's wrist so that there is little likelihood of its pinch-

ing the skin while being positioned on the wrist.

The ribbon-like wrist band of the present invention also has its outside surface buffed, ground or otherwise actuated upon so as to eliminate the natural round contour of the wire strand used to fashion the expandable ribbon. In the present instance, a wire strand that is substantially circular in cross-section constitutes the material from which the wrist band is fashioned. As best shown in Fig. 4, a portion of its circumferential area, which in the present instance is that portion disposed outwardly of wound loops, is suitably ground away, after winding, to provide a flat surface area 15. The presence of this flat area on each of the loops constituting the completed article greatly enhances its over-all appearance due to the creation of planar surfaces having light reflecting characteristics different from that of the round surface areas adjacent thereto. Such grinding also enables the use of round stock without detracting from the appearance of the finished article.

It should be understood that although a specific form of wrist band has been illustrated in the accompanying drawing and that the strand illustrated is circular in cross-section, the wrist band of the present invention may be shaped otherwise than as shown and further may be fashioned from a strand having a cross sectional area different from that illustrated, such as, for example, from flat or square stock, without departing from the spirit of the invention or the scope of the appended claims.

I claim:

1. An expandible bracelet comprising a ribbon-like band fashioned from a single strand of material coiled into a continuous succession of closely related elongated loops with the transversely extending reaches of each of said loops being bowed toward each other and connecting tangentially with substantially semi-circular portions to provide a band of less thickness at the longitudinal center than at the edges thereof.
2. An expandible bracelet comprising a helically wound spring, the coils of which are elongated, the elongated portions of said coils being bowed in opposed relationship and connecting tangentially with substantially semi-circular end portions to provide a band having opposed concave surfaces.

ALLEN BENJAMIN.
